UNITED STATES PATENT OFFICE.

ALLEN D. CARDWELL, OF BROOKLYN, NEW YORK.

TELEGRAPH TYPE-WRITER.

1,218,165.

Specification of Letters Patent.

Patented Mar. 6, 1917.

Application filed April 10, 1915. Serial No. 20,386.

To all whom it may concern:

Be it known that I, ALLEN D. CARDWELL, a citizen of the United States, and resident of New York city, borough of Brooklyn, in the county of Kings and State of New York, have invented certain new and useful Improvements in Telegraph Type-Writers, of which the following is a specification.

Some of the general objects of my invention are to provide a telegraph typewriter which shall be simple, durable and positive in operation, and that may operate at maximum speed and with greatest possible accuracy, and so arranged that it may be operated over an ordinary Morse telegraph line, or any other desired circuit.

My invention relates to improvements in telegraph typewriters comprising a type member or wheel having annular rows of type spaced apart, and wherein such type member or wheel is given a rotary or vertical movement, or a rotary and vertical movement, to bring various type thereon into printing position as required. In Letters

25 Patent No. 1,070,407, granted to me August 19, 1913, I have illustrated a telegraph typewriter wherein the type member or wheel is normally at rest in a position with a space of the wheel, between vertical columns of type, opposed to a hammer and midway between the upper and lower annular rows of type on the wheel, which wheel is adapted to be rotated to the right or left of said normal position to a position between any other two columns of type, and then to be further rotated to the right or left one or more spaces, or the fraction of a space, to bring the desired type into printing alignment relative to the hammer, and whereby also said type 40 member or wheel is to be moved longitudinally a half space, or a space and one-half, to bring type of a column opposite to the printing hammer, as required. In my said patent electrically operating mechanism is set forth whereby the above-mentioned 45 movements of the type member may be produced by currents of different direction and duration as required.

My present improvements are directed, to some extent, to certain improvements upon the mechanism of my said patent, and to the manner of operating magnets and relays, whereby the apparatus may be operated by current of the same direction and duration, and whereby a progressive movement of the type member may be made from a normal

position of rest or from a new normal or "figure-shift" position directly to the printing position, and whereby also a progressive movement of said type wheel in its longitudinal direction may be made, from either of said positions, directly to a position of use opposed to the printing hammer, without requiring the type member to be given an additional movement in any direction when once brought to rest.

In accordance with my present invention I provide means for rotating the type member from its normal position of rest to the said new normal or a second position of rest, which I term the "figure-shift" position, which is equal to a partial rotation of said member, say a little more than one-half of its circumference, and the apparatus is so arranged that the characters on the type wheel between said two positions (or on the first portion of the wheel) may be brought directly or progressively to the printing position as required, and after said member has been rotated to the second or "figure-shift" position, the same mechanism will operate the member to bring the characters of the second portion thereof into the printing position, in the same manner that they are brought to the printing position on the first portion of the member. After the character or characters of the second portion of the type member or heel, as so shifted, have been printed, as desired, the member may be released from the said "figure-shift" position and returned to the normal or first position of rest.

In the specific embodiment of the type member herein disclosed, I have provided for forty-eight characters thereon, in four annular rows and twelve columns, which member may be considered to have a first portion containing seven columns of characters for normal use, and a second portion containing five columns of characters for use in and from the "figure-shift" position. I have so arranged the mechanism that the type member normally may have a column of type in vertical relation to the hammer in the normal or zero position (with preferably no character on the annular row opposing the hammer in such position), and whereby from such normal position the type member may be rotated six spaces without regard to the "figure-shift" position for normal use, and whereby after the type member has been rotated directly to the "figure-

shift" position the first column of type of the second or "figure-shift" portion of the wheel will be brought into vertical relation to the hammer, and then the wheel may be rotated from such "figure-shift" position one or more spaces progressively forward to bring any desired column of type on the second portion of the wheel or a limited number of characters of the first portion in position with relation to the printing hammer. Other features regarding the arrangement and operation of the type member will be hereinafter pointed out.

My improvements also embrace novel means for controlling movements of the carriage, such as for its step by step feeding movement, back spacing, and return to the normal line-starting position; for feeding the paper; for line spacing; for operating the printing mechanism; for controlling the inking ribbon, and for other purposes, as will be more fully hereinafter explained.

Various magnets are provided for controlling the operation of the type member, printing mechanism, carriage, and ribbon devices above referred to, and means are provided for controlling the operation of said magnets as required. While my improvements may be used in connection with any suitable transmitting or translating apparatus, it may be advantageously used in connection with the transmitting and translating mechanisms shown in my applications Serial No. 801,813, filed Nov. 19, 1913, and Serial No. 860,318, filed Sept. 5, 1914, or with any suitable portions thereof.

In the diagrammatic illustration shown in Figure 15 hereof, I have illustrated an improved circuit system embracing devices of the aforesaid applications for the purpose of controlling the magnets of my present invention, and in order to indicate parts of my said application as illustrated in Fig. 15 hereof, I utilize therein reference characters of corresponding parts, as nearly as possible, from my said applications. In accordance with the said diagrammatic view, a series of contacts are to be successively operated for each character to be printed, and for the various controlling devices of my improved telegraph typewriter, which contacts receive signals on the line as required, the contact arrangement being shown substantially similar to that disclosed in my said application Serial No. 860,318, whereby when current passes through any of said contacts, corresponding relays will be operated to cause appropriate operation of the magnets of my improved telegraph typewriter for the purposes above stated.

My invention, however, is not limited to be used in connection with the apparatus of my said applications, nor with the devices and circuits shown in Fig. 15 hereof,

although the latter is particularly adapted for use in conjunction with my present telegraph typewriter.

My invention further comprises novel features of improvement that will be more fully hereinafter set forth and then pointed out in the claims.

Reference is to be had to the accompanying drawings forming part hereof, wherein,

Fig. 1 is a plan view of my improved telegraph typewriter showing the parts in their normal positions, certain overlying parts being removed;

Fig. 2 is a view similar to Fig. 1, showing the type member and certain parts in the "figure-shift" position;

Fig. 3 is an enlarged plan view of parts shown in Figs. 1 and 2, illustrating the shaft of the type member in its extreme position;

Fig. 4 is a detail of Fig. 3, parts being removed;

Fig. 5 is a further detail of Fig. 3;

Fig. 6 is a section substantially on the line 6, 6, in Fig. 2, parts being omitted;

Fig. 7 is a transverse section taken substantially on the line 7, 7, in Fig. 8;

Fig. 8 is a vertical section substantially on the line 8, 8, in Fig. 7;

Fig. 11 is an inverted plan view of Fig. 9;

Fig. 12 is an edge view, partly in section, looking from the righthand side of Fig. 9, 105 the paper carriage and type member being omitted;

Fig. 13 is a sectional detail of the inking ribbon devices;

Fig. 14 is a development of the type member, and

Fig. 15 is a diagrammatic view, illustrating electrically operating devices and circuits adapted to control various devices of my improved telegraph typewriter.

Similar numerals of reference indicate corresponding parts in the several views.

At 10 is indicated a suitable frame shown provided with a standard 11 having suitable bearings in which is journaled a shaft 12. Upon said shaft is slidably mounted a type member or wheel 14, which is splined to said shaft to rotate therewith. The printing characters on said member or wheel 14 may be arranged in any desired manner. In the example illustrated I have shown said type member as provided with four annular rows of type arranged in twelve vertical columns, such rows being suitably spaced apart. At 15 is a printing hammer

(Fig. 6) that is normally retracted from the type and in position opposite one of the annular rows of type when type member 14 is in the normal position of rest. I have shown the type member 14 with its upper annular row 14^a of type normally opposing hammer 15, said member 14 being adapted to be raised, in different steps, to bring its lower annular rows of type opposite hammer 15 as required. In the diagrammatic illustration of the type member 14 (Fig. 14), the same is shown provided with twelve facets or divisions comprised in each annular row, the upper row containing two blank spaces 14^b, 14^c, the other facets or divisions of such row containing letters, figures, etc., while the other three annular rows each contain letters and figures, punctuation marks and the like. The blank spaces 14^b, 14^c on the upper row of member 14 are for the normal and figure-shift positions of said member, the space 14^b normally resting opposed to hammer 15, and the space 14^c being the new position of rest of member 14 when it is moved to the "figure-shift" position, whereby when member 14 rests in either of said positions operations of the printing hammer may occur without printing any character. The portion of type member 14 containing the first seven vertical columns of characters, (reading from the left in Fig. 14), comprises the normal or first operating portion of member 14, whereby said member may be moved to bring any of said letters in printing position opposite the hammer by direct or progressive action of the devices hereinafter described, and the remaining or second portion of member 14, containing five columns beyond said first portion, corresponds to the "figure-shift" position, so that said member 14 may be shifted from its first or normal resting position or zero (with space 14^b opposite the hammer) directly to the second or "figure-shift" position, with the space 14^c opposed to the hammer, whereby when said member is in such position it may be operated by the aforesaid devices to directly or progressively present any of the characters of the second portion of said member opposite the hammer for printing figures, punctuation marks, etc. Said member then may be released from the "figure-shift" position to return to its first normal position, for further printing of letters, etc. Since I have provided blank space 14^b and 14^c on member 14, and made no provision on the "figure-shift" or second portion of said member for the numeral "1" and cipher "0," I utilize the letters "I" and "O" for such numerals. Said letters are shown located in the first column under the space 14^b, and I have so arranged the apparatus that when the numeral "1" or the cipher "0" is to be printed, (when numerals are being

printed, or the member 14 has been shifted to the figure shift position), the member 14 may be moved five spaces from the "figure-shift" position to bring the letter "I" or "O" into printing position by the depression of the appropriate key of the transmitting key board indicating the numeral 1 and the cipher. The foregoing may occur notwithstanding that the appropriate key of the keyboard for the letter I or O also causes the bringing of such letter opposite the hammer, by reason of the shifting upwardly of member 14 without rotating the same, as hereinafter explained.

The means I have shown for rotating member 14 for bringing the desired character of the second portion of said member into printing relation to hammer 15 (according to whether member 14 is or is not raised from its normal position of rest, Fig. 6), is as follows: At 16 is a pinion secured upon shaft 12, and shown having twelve teeth, said pinion being in mesh with a toothed segment or sector 17 on the end of oscillating arm 18 (Figs. 6 and 7). Said arm is pivotally carried by rod or shaft 19 pivotally supported by plate 10^a and bracket 19^a of frame 10. Beneath arm 18 is an arm 20 secured on shaft 19. Between said arms is a plate 21 having a slot 21^a receiving shaft 19 and a slot 21^b receiving a screw or stud 22 secured on arm 20, whereby plate 21 may slide relatively to and be guided upon arm 20. Between arm 18 and plate 21 is an arm 23 that is pivotally supported upon a stud or screw 24 secured on arm 20 and which is received by slot 21^a of plate 21. Arm 23 is provided with a slot or opening 23^a freely receiving shaft 19 (Fig. 6). Arm 23 has a stud screw 25 having roller 25^a working in an angularly disposed or cam-slot 26 in plate 21 (Figs. 3, 4 and 6), whereby, as said plate 21 is reciprocated, the arm 23 will be rocked, arm 23 being provided with a transverse slot 23^b receiving stud or screw 22, whereby lateral movement of arm 23 is permitted relatively to plate 21. At 27, 28 are a pair of spring fingers pivotally supported upon shaft 19 between arms 18 and 23, and receiving between them a pin or projection 29 depending from arm 18 and a pin or projection 30 upstanding from arm 23. A spring 31, shown encircling shaft 19 and having its ends bearing against arms 27, 28 (Fig. 3) tends to hold said arms 18 against stop 30 and thereby to maintain arm 18 resiliently in normal position or central with relation to plate 21. A spring 32 connected with arm 18 by the stop 33 and connected to an extension 20^a on arm 20 (Fig. 3) normally tends to return arm 18 to its normal position. It will be understood that when arm 20 is moved upon the axis of shaft 19, the arms 18 and 23, the plate 21, and the spring fingers 27, 28 all 130

move equally with it; and that when plate 21 is slid relatively to arm 20, the arm 23 is moved upon the axis of stud 24 by reason of the walls of the slot 26 engaging the roller 25^a on the screw 25, but independently of arm 20, and that thereupon arm 18 is rotated around shaft 19 to the same extent as arm 23 by reason of the projection 30 engaging the arm 27 or 28, causing the latter, 5 through the projection 29, to move arm 18, whereby the latter may have movement independent of arm 20. The resiliently acting parts 27 and 28 permit arm 18 to have slight overthrow at the end of a stroke without injury to the parts. Portions of the foregoing parts are somewhat similar to analogous parts in my aforesaid Patent No. 1,070,407. At 34 are stops (Figs. 3 and 6) on frame 10, spaced apart in position to 10 check any undue overthrow of arm 18. I provide means for moving arm 20 and with it arms 18 and 23 from normal in two different manners, viz: the first movement to rotate pinion 16 and type member 14 a 15 definite number of teeth of said pinion from normal for the first portion of said member, by means controlled by character selecting signals or impulses on the line to operate arm 18 and pinion 16, and, second, to move 20 the arms 18, 20 and 23 directly to the "figure-shift" position, by means controlled by figure-shift-selecting signals or impulses on the line, to bring the second portion of member 14 to the second normal or "figure-shift" position, from which position said member also may be rotated by arm 18 and pinion 16. To this end, in either of the said 25 positions of type member 14, the plate 21 may be moved or slid by means controlled 30 by appropriate character-selecting signals or impulses on the line to move arm 18 to rotate type member 14 one or more teeth of pinion 16, either without or in addition to, the movement of said arm 18 and member 14 by either of the aforesaid movements of arm 20. The means I have shown for 35 operating arm 20 by character-selecting signals or impulses on the line (as distinguished from its movement to "figure-shift" 40 position), comprises a magnet 1^a, shown supported upon frame 10, whose armature is pivotally connected with an arm or the like 35, which rod is pivotally connected at 36 with an arm 37 (Figs. 1, 2, 3, 4, 5, 6) 45 that is pivotally connected with the armature σ' of the "figure-shift" magnet O. The arm 37 is shown located beneath arm 20 (Fig. 6) and is provided with an angularly disposed or cam-like slot 37^a (Fig. 5) receiving a stud or screw 38 carried by arm 20 (Fig. 6), whereby, when the armature of magnet 1^a is attracted, the arm 37 and its slot 37^a will be moved to cause stud 38 to shift arms 20, 23 and 18 together, to cause 50 member 14 to be rotated a number of teeth 55

of pinion 16, the member 14 being rotated the distance of four of such teeth in the example illustrated. Arm 20 is retained in and returned to its normal position by means of a spring 20^b (Figs. 1 and 2). 70

Arm 18 may be operated the distance of one, two or three teeth of pinion 16, in the example illustrated, either independently of or in conjunction with the operation of said arm by magnet 1^a, by means of character 75 selecting signals or impulses on the line. To this end I provide magnets 2^a and 3^a (Figs. 1 and 2) having a common armature 3^a that is pivotally connected, at 39, with a link 40, which is pivotally connected at 41 80 with slide 21, as by the interposed arm 42 (Fig. 6). By this means, when armature 3^a is attracted by either of the magnets 2^a or 3^a, or by both operating together, slide 21 will be pushed to cause its cam slot 26, 85 in conjunction with the stud 25, through the medium of the parts 28 and 29, to swing arm 18 around shaft 19, Figs. 1, 2 and 3. The spring 3^b connected with armature 3^a normally draws the latter against a back- 90 stop 43 (Figs. 1 and 2), thereby returning arm 18 to its normal position relative to the magnets 2^a and 3^a. In order that arm 18 may be moved one or more steps by magnets 2^a and 3^a, as the character to be selected requires, I provide movable stops 2^{a'} and 3^{a'}, 95 corresponding respectively to the magnets 2^a and 3^a, which stops are normally retained in the path of armature 3^a, and are adapted to be pulled out of the path of said armature to permit the latter to be attracted one, two or three steps as required. Springs 44 and 45 (Fig. 6) are adapted to retain said stops in their normal positions. Said stops are shown guided in and projecting through 100 plate 10^a of frame 10, and at their upper ends slide in a guide or bridge 46 on said frame. Magnets 2^{a''} and 3^{a''}, respectively in series with the magnets 2^a and 3^a, control the stops 2^{a'} and 3^{a'} respectively, so that 110 each time one of the magnets 2^a or 3^a is energized, the corresponding stop 2^{a'} or 3^{a'} will be moved out of the path of armature 3^a, and if both of said magnets are operated for a character, both of said stops will be 115 moved out of the path of said armature. The pivots or shafts of the armatures of the magnets 2^{a''}, 3^{a''}, are respectively provided with arms 47, 48 (Fig. 6) engaging nuts or enlargements shown at the lower 120 ends of the stops 2^{a'} and 3^{a'}, whereby when said armatures are attracted, said stops will be moved out of the path of armature 3^a, the springs 44, 45 serving to retract the armatures from magnets 2^{a''} and 3^{a''} as said 125 stops are restored to their normal positions. With this arrangement it will be understood that, if a character signal is transmitted to the magnet 3^a, it will attract armature 3^a (and stop 3^{a'} will be moved, but 130

without affecting the stroke of the armature) as said armature will then be arrested by stop 2^d, and plate 21 will thus be moved one step to cause arm 18 to swing the space of one tooth of pinion 16, to rotate type member 14 one space or type character from normal, to bring such character in vertical alinement with hammer 15. If a character signal causes the operation of magnet 2^d alone, its stop 2^d will be moved, and the armature 3^e will move two steps or the space of two teeth on pinion 16, and come to rest against said stop 3^d, thereby rotating type member 14 the space of two of its 10 type from normal. If a character signal energizes both magnets 2^d, 3^d together, both of their stops 2^d and 3^d will be moved out of the path of armature 3^e, and (as said armature is then attracted by both magnets) it will move the space of three steps or the space of three teeth of pinion 16, thereby rotating member 14 the space of three type characters to bring the corresponding type in vertical alinement with the 15 hammer, the armature 3^e at such time coming to rest against stop 43^a (Figs. 3 and 6). From the foregoing it will be understood that if a character that is spaced one, two, three or four spaces on the member 14 from normal is to be printed, either magnet 3^d or 2^d, or 3^d and 2^d together or magnet 1^d, will be operated to rotate member 14, one, two, three or four steps. If, however, a type character more than four 20 spaces on member 14 from its said normal position is to be printed, then magnet 1^d, together with magnet 2^d or 3^d, or 2^d and 3^d together, will be operated. Thus, if member 14 is to be rotated the space of five type 25 characters, magnet 1^d will be operated to rotate said member four spaces and magnet 3^d will be operated to rotate said member one space; if the sixth type from normal is to be printed then magnets 1^d and 2^d will be 30 operated for rotating member 14 six spaces, and if the seventh type from normal is to be printed the magnet 1^d and magnets 2^d and 3^d will all be operated, thereby rotating member 14 the distance of seven type or 35 seven teeth on pinion 16. Such movements of pinion 16 are permitted because when magnet 1^d causes arm 20 to swing arm 18 the distance of four teeth of pinion 16, the parts 20, 21, 23, 28 and 18 move together, and magnets 2^d and 3^d may move arm 18 farther from the position to which it is brought by magnet 1^d, by reason of the independent movement of arm 23 with relation to arm 20 as caused by plate 21 when operated by armature 3^e. It is immaterial whether armature 3^e is operated before or after the armature of magnet 1^d for a given series or group of character selecting signals or impulses for said magnets. 40 The above described operations of arm 18 and type shaft 12 may be considered to occur with member 14 in its normal position of rest, for printing characters from its first portion carrying type letters, and similar operations may occur after member 14 has been advanced to its "figure-shift" or new normal position, for rotating said member desired steps from such position. Thus, the armature O' of magnet O is normally retained against a back stop O'' (Fig. 1) 45 by a spring o² (Fig. 3) (assisted by spring 20^b), and at a suitable distance from said back stop is a movable stop 49 shown guided in plate 10^a of frame 10 and in a guide 52, said stop being in position to be pushed upwardly by spring 53 into the path of armature O' when the latter is attracted by magnet O (Figs. 2 and 8^a). The arrangement is such that when armature O' is against back stop O'' the movable stop 49 50 will be held down by engaging the overlying armature O' (Figs. 1 and 8^a), and when said armature is attracted by magnet O (by reason of a signal for the "figure-shift" position of member 14), said armature will pass 55 beyond stop 49, which will spring up behind said armature and retain the latter temporarily in its attracted position. The magnet O may be controlled by a key on the transmitting key-board marked "Fig-shift". 60 When magnet O attracts its armature the arm 37, by means of the pin and slot connection 37^a, 38, moves arms 20, 27, 28, 18 and 23 and slide or plate 21 to a new or "figure-shift" position (swinging rod 35 on its 65 pivots relative to magnet 1^d), (Fig. 2), and thereby type member 14 is rotated beyond its first portion and comes to rest with the column of type under space 14^e in vertical alinement respecting hammer 15, with said 70 space opposed to said hammer. While member 14 is thus retained in such new normal or "figure-shift" position (by stop 49) the operation of magnets 1^d, 2^d, 2^a, 3^d, 3^a, and the stops 2^d and 3^d may be carried out, as before 75 described, for rotating member 14 forwardly from such "figure-shift" position to cause any of the type of such second portion of said member 14, (as for instance, numerals, punctuation marks, etc., thereof) to be 80 brought in vertical alinement with respect to hammer 15, as required, in accordance with the character to be printed. 85 When desired, the member 14 can be operated from the "figure-shift" position beyond the second portion of said member to bring one or more type of the first portion into vertical alinement with hammer 15, as, for instance, to utilize the characters O and I for the cipher and numeral 1 respectively 90 without requiring the member 14 to be released from "figure-shift" position and restored to normal under the column 14^a. For instance, if it be desired to print any number not containing "I" or "O," or a punctua- 95

tion mark or the like, the magnet O will be operated, causing arm 18 to be rotated to the new normal or "figure-shift" position (Fig. 2) where said arm will be retained by the 5 stop 49 engaging armature O'. With arm 18 in such position the magnets 1^a, 2^a, 3^a may be operated, as required, to rotate member 14, one, two, three or four spaces, in the same manner as before described, to bring 10 the columns containing the desired characters in vertical alinement with hammer 15, as many times as desired, arm 18 returning to the new normal or "figure-shift" position each time that a character in the second portion 15 of member 14 is printed. Should, however, (in the example illustrated) it be desired to print a number containing the figure "I" or "O", as for instance, the number 51, the arm 18 will first be moved to the "figure- 20 shift" position by operating the "Fig.-shift" key of the keyboard, thereby rotating member 14 to the new normal or "figure-shift" position; then the key corresponding to "5" will be operated, whereupon the magnet 1^a 25 will cause arm 18 to be operated from the "figure-shift" position to bring the column of member 14 containing type "5" in vertical alinement with hammer 15, and after that figure is printed the magnets 1^a and 3^a will 30 cause arm 18 to move sufficiently far to rotate member 14 five steps or one column beyond its second portion to bring the column on its first portion containing the "I" around into vertical alinement with hammer 15, 35 (the member 14 also being shifted in a longitudinal direction the space of one row of type, as hereinafter described), without first releasing arm 18 from the "figure-shift" position. After such "I" is printed arm 18 40 may be released and restored to normal, to return member 14 to the normal position. Any successive numbers may be printed without releasing member 14 from the "figure-shift" position. By this means of 45 causing member 14 to advance beyond its second portion in order to print the numerals "I" and "O" that are on the first portion of said member, the twenty spaces allotted to the second portion of member 14 50 (in the example illustrated) may be utilized for a blank space at 14° for the normal "figure-shift" position of said member and for nineteen other characters additional to the "I" and "O." Of course, the I and O 55 can be placed upon the second portion of member 14 in the event that sufficient other characters are not placed thereon to make up the allotted twenty spaces. Thus, with the twenty spaces on the second portion of member 14 and twenty-eight spaces on its first portion I am enabled to utilize the equivalent of forty-eight characters notwithstanding 60 the two blank spaces at 14° and 14°.

65 When it is desired to release arm 18 from its figure shift position, the stop 49 is with-

drawn from armature O' by means of a suitable signal sent on the line, as from a key of the keyboard marked "Fig.-release" or by the space bar. To this end I provide a magnet S shown carried upon the under 72 side of the plate 10° of frame 10 (Figs. 8 and 8a) the armature of which magnet has an arm S' engaging an enlargement 49' on said stop 49, whereby when magnet S is energized stop 49 will be pulled down. When 75 it is desired to restore arm 18 to its normal position, the "Fig.-release" key or space bar is operated to cause energization of magnet S and said magnet is shown in circuit with magnets Q and R (Fig. 15), so that when 80 certain other operations are performed the type member 14 may be restored to normal after it has been shifted to "figure-shift" position, as hereinafter explained.

It may be here stated that the particular 85 arrangement of type upon member 14, herein shown and described, is not essential in the construction or operation of my apparatus, since member 14 may have any desired number of characters in a column and 90 any desired number of characters in an annular row, as, for instance, four annular rows each containing sixteen characters, in which event eight columns would be allotted to the first portion of member 14 and eight 95 columns would be allotted to the second portion thereof. This arrangement will provide for thirty-two characters on each portion of member 14, and the number of movements given arm 18 by the magnets 1^a, 2^a, 3^a from 100 normal, or from the "figure-shift" position, would correspond to seven steps beyond the normal position, instead of six steps for the first portion of member 14 as shown in Fig. 14. In such event it would not be necessary 105 to advance member 14 beyond its second portion from the "figure-shift" position to bring type of its first portion (such as for "I", "O") into printing position, since such "I", "O" can be included in the second 110 portion of said member, with any other desired characters.

In the description so far given it may be understood that member 14 has been considered in its normal position with one of 115 its marginal rows (14°) of characters in normal relation to hammer 15, said member being illustrated with its upper row of characters opposite said hammer (Fig. 6), although any other desired row may be normally retained opposite to said hammer. If the upper or the lower row of characters on member 14 be normally retained opposite hammer 15, then the other rows may be brought opposite said hammer by a progressive longitudinal movement of member 14 120 in one direction. If one of the rows intermediate the marginal rows of said member should be normally retained opposite said hammer, (or if the space between any two 125

rows should be retained opposite said hammer, as illustrated in my Letters Patent No. 1,070,407, aforesaid), then member 14 would be moved longitudinally in one or another direction the required step or steps to bring the desired row of characters opposite said hammer for printing. Considering member 14 as in the normal position shown in Fig. 6, and having four annular rows of characters, then at any time that a character is to be printed that is in the top row of member 14, it is merely necessary to rotate said member the required distance to bring the desired character in front of the hammer, and then to operate the hammer, but if the desired character is in a row below said top row the member 14 will be raised the required step or steps to bring the desired row opposite the hammer, and will be rotated to bring the desired character of said row opposite the hammer, unless the character desired is in the normal or "figure-shift" position, and then the hammer will be operated to print. To this end I provide member 14 with an annular groove 14^a (Fig. 6) receiving a pin or the like 56^a projecting from an arm 56 shown pivotally supported at 57 upon a frame or bracket 58 carried by frame 10 (Figs. 1, 2, 6, 7 and 8). In the example illustrated arm 56 is raised the space of two rows of characters of member 14 by the operation of a magnet 4^a (Figs. 1, 2, 7 and 15) as follows: The armature 4^a of magnet 4^a is normally retracted by a spring against a suitable stop, and said armature is connected to a rock shaft 59 journaled in bearings upon plate 10^a, from which shaft is an upwardly extending arm 60, (Fig. 8). The arm 60 is provided at its upper end with a fork or slot 60^a, receiving a stud 61 projecting from a bar or rod 62, the lower end of which is pivotally connected at 63 with a rock arm 64, (Figs. 1, 2 and 8). The upper end of bar or rod 62 is provided with an inclined or cam-like slot 62^a receiving a projection 65 carried by arm 56. The normal position of such parts is shown in Fig. 8, and the arrangement is such that when magnet 4^a attracts its armature, (and thereby rocks arm 60 to the right in Fig. 8), the bar 62 will be correspondingly moved to the right and its cam slot 62^a, coacting with projection 65, will raise arm 56 a distance equal to the distance of two rows of type of member 14, so that the third row 14^a from the top will be brought opposite hammer 15. Arm 56 is shown provided with a part 56^a (Fig. 3) working on a guide 66 adapted to steady and guide said arm. To cause type member 14 to be moved longitudinally the distance of one row of type (Fig. 6) from the normal position I provide a magnet 5^a, shown carried by and depending from plate 10^a (Fig. 8) the armature of which magnet is normally attracted by a spring 5^y and held against a suitable stop. Said armature is connected to arm 64 whereby when said magnet 5^a is energized and attracts its armature the arm 64 will raise the bar 62 (its stud 61 now sliding freely in fork 60^a of arm 60 which remains stationary), and thereby projection 65 is raised, causing arm 56 to be raised the distance of one row of type of member 14 to bring the row 14^a opposite hammer 15. When the fourth row 14^b is to be raised into opposition to hammer 15, the magnets 4^a and 5^a are both operated, whereby when magnet 4^a attracts its armature the bar 62 will be moved to the right, and slot 62^a will cause arm 56 to be raised the space of two rows of type and arm 64 will be raised causing arm 56 to be raised a further step, to bring the row of type 14^b opposite the hammer. It is not material in what order the magnets 4^a and 5^a are energized when operating conjointly. Furthermore, member 14 may be rotated to bring the desired column of characters in vertical alinement with hammer 14 and then moved longitudinally to bring the desired row of such characters opposite said hammer, or such operations may be reversed. In the diagrammatic illustration of Fig. 15 the arrangement is such that member 14 is first rotated and then moved longitudinally to bring a desired type character opposite the hammer for the first portion of member 14, and when the second portion of said hammer is to be utilized, the magnet O is first operated to rotate member 14 to the "figure-shift" position, and then said member is operated, as before described, to bring the desired character opposite the hammer.

The printing hammer 15 is shown carried upon a plate 10^b, removably secured upon plate 10^b and spaced a suitable distance above the latter (Fig. 6). Hammer 15 is shown guided to reciprocate within a suitable barrel or tube 15^a, said hammer having a shoulder against which a spring 71 bears, which spring also bears against a stop 15^c within tube 15^a. Said tube is shown provided with a removable cap 15^b through which the stem of the hammer is guided (Figs. 6, 9, 10 and 12). Hammer 15 is shown projecting beyond plate 10^b over the paper roll on the paper carriage, the paper to be printed being located between the hammer and member 14 (see Fig. 9). A magnet T is carried by plate 10^b and its armature T' is in position behind the hammer to thrust the hammer forward to print when the magnet is energized. In order to move the hammer to one side to permit the ready insertion and removal of the paper carriage, said hammer and its tube 15^a are carried by a member 72, shown pivotally supported at 73 on plate 10^b and normally retained in the operative position by a spring 74 shown

connected with pins on plate 10^b and member 72 (Fig. 9), said spring serving to draw member 72 normally against a stop 75 on plate 10^b. Armature T' is shown provided with a tongue-like spring 76 suitably curved and adapted to engage the end of hammer 15 when the latter is swung from its normal position, to resist the tension of its spring 71, thereby to cause the hammer to be guided back to proper position in front of adjustable stop T² of magnet T' in the normal position of the hammer. The arrangement illustrated in Fig. 15 is such that hammer 15 is operated to cause printing after the 15 desired character on member 14 has been brought to the printing position.

In order to assure the accurate printing position of member 14 I provide improved means for causing member 14 to be retained set or alined in printing position. To this end I have shown two arms 77 and 78, which are movably supported upon a rock shaft 79 secured to the armature q of a magnet Q that is carried by plate 10^a (Figs. 1, 3 and 6). The arm 77 operates an alining pawl or projection 81 that is adapted to engage a star wheel 16^a secured to shaft 12, being shown integral with pinion 16 (Figs. 6 and 8) to hold the type member 14 rigid, and to bring it into exact printing position if it should be slightly out of alinement before the stroke of the hammer. The pawl 81 is shown carried by a lever 82 pivotally carried by the standard 11. The arm 78 is provided with teeth 78^a spaced apart corresponding to the distance between the rows of type upon member 14, which teeth are adapted to engage a correspondingly shaped projection 56^b on arm 56 (Figs. 6, 7 and 8). The arms 77 and 78 are resiliently connected with shaft 79 by means of springs 83, 83' respectively, (Figs. 6 and 8) which springs bear at one end against the corresponding arm and at their opposite ends are secured to a saddle 45 or the like 84 that is secured to shaft 79 and which lies in front of said arms 77, 78 in such position that said springs may normally hold said arms in contact with said saddle, (Fig. 6). When magnet Q is energized its armature rocks shaft 79 and thereby causes arms 77 and 78 to swing to the left in Fig. 6, carrying the pawl 81 into engagement with star wheel 16^a, and carrying a tooth 78^a into engagement with the projection 56^b, with a resilient action, whereby member 14 is centered or alined in a rotary direction and arm 56 is centered or alined in a vertical direction. The retracting spring of armature q normally draws arms 60 77 and 78 rearwardly when the magnet Q is deenergized. Magnet Q is in circuit with printing magnet T so as to assure the proper alining of member 14 when hammer 15 is operated, as shown in Fig. 15.

65 To provide the required space between

each character printed, as well as to provide spaces between words and the like, I provide means for feeding the paper carriage step by step by the action of magnet R, in conjunction with devices as follows: Upon the underside of plate 10^b is secured magnet R whose armature R' is shown pivotally connected with a spring-acting pawl or dog 85 adapted to engage the ratchet wheel 86 of a spring drum 87 (Figs. 9, 10, 11), which drum is provided with a gear 88 in mesh with a rack 89 carried by the paper carriage 90. The arrangement shown is such that when armature R' is attracted its pawl 85 slips over a tooth of ratchet 86, and when the spring 91 retracts or pushes back said armature said ratchet and gear 88 will be rotated the space of one tooth to feed the paper carriage a corresponding step forward. In Fig. 15 magnet R is shown in circuit with the printing magnet T, whereby each time the hammer operates, the paper carriage will be fed a step for a letter space. The same operation is performed for feeding the carriage a word space (without operating printing magnet T) by means of electrical devices hereinafter explained in conjunction with a suitable key of the transmitting keyboard. Carriage 90 is shown provided with guide rails or the like 92, 93, (Figs. 9 and 11) resting upon guiding rollers 94 pivotally carried by the main frame.

In order to back-space the carriage, I provide magnet N which is shown secured upon the under side of plate 10^b (Fig. 11), the armature N' of which is pivotally connected with a rod or bar 95, which in turn is adapted to push upon a pin or projection 96 on link 105 that is pivotally attached to a retaining dog 97 pivotally supported at 98 on plate 10^b and having a spring 99 normally causing said dog to engage ratchet 86 to prevent it from unwinding under normal conditions. A second dog 100 is shown pivotally supported upon plate 10^b, at 101, 105 which dog is pivotally connected with bar 95 at 102 (Fig. 11) and normally pushed toward ratchet 86 by spring 103, the relation of the parts, however, being such that when spring 104 retracts bar 95 and armature N' 115 from magnet N, the dog 97 will remain in engagement with ratchet 86, but the dog 100 will be maintained out of engagement with said ratchet. The relation of the operating ends of dogs 97, 85 and 100 with respect to ratchet 86 is such that when armature N' is attracted, the bar 95, by pushing upon pin 96, will cause dog 97 and pawl 85 through the medium of link 105, to release ratchet 86 and simultaneously throw dog 100 into 125 the path of a tooth of such ratchet in such position as to permit said ratchet to rotate one-half space of one of its teeth, the dog 100 then retarding the ratchet, and when armature N' is retracted the dog 100 will 130

be withdrawn from ratchet 86 and the dog 97 and pawl 85 will check the ratchet after it has moved the space of the remaining half-tooth. It will be understood that as ratchet 86 is normally under the tension of the spring drum, tending to unwind in the direction of the arrow *a* in Fig. 11, and return the carriage toward its starting position, that each time that magnet N is operated the carriage may move back one step or the equivalent of one character of type member 14. By means of a suitable key on the keyboard current may be caused to flow through magnet N when it is desired to back space the carriage, as hereinafter explained in connection with Fig. 15.

In order to cause the carriage to return to its initial or normal position, the pawl 85 and dog 97 are to be released from ratchet 86 simultaneously, to permit the spring-drum to rotate the ratchet 86 and gear 88 in the direction of the arrow *a* in Fig. 11, but without interruption, until the carriage is arrested at the starting point, still under the tension of the spring-drum. To this end I provide a magnet P which is shown carried on the under side of plate 10^b (Fig. 11) whose armature P' is normally retracted by spring 106 against a movable stepped stop 107 (Fig. 12) that is pivotally supported at 108 upon plate 10^b and normally pressed down by spring 107^c secured on said plate (Fig. 10), the armature P' as drawn by spring 106 normally resting against the lowermost shoulder or step 107^a of stop 107. When armature P' is attracted it engages the pin 96, trips the dog 97 from ratchet 86 and, by pushing the link 105, withdraws pawl 85 from ratchet 86, and said armature 40 also moves away from stop or shoulder 107^a, wherenpon stop 107 is pushed down by its spring 109 to cause its shoulder or stop 107^b to engage said armature and retain it in the attracted position. The spring drum thus being released causes gear 88 to operate rack 89 to return the carriage to the normal or marginal position. Armature P' remains set in such position until the carriage is returned to normal, and thereupon a projection 89^a shown carried by rack 89 (Figs. 10 and 11), engages the beveled or inclined end 109^a of tripper arm 109 that is shown pivotally carried at 110 upon the under side of plate 10^b (Fig. 10), which tripper arm, by 55 reason of a pivotal connection thereof at 111 with stop arm 107, causes said arm to be tilted to raise its stop 107^b from armature P' and to bring its stop 107^a again to the normal position in front of said arm in its 60 normal retracted position. Said armature thereupon releases pin 96, wherenpon the dog 97 and pawl 85 are restored to their normal positions in coaction with ratchet 86, the spring drum thereby being again retained in a wound condition ready to be fur-

ther wound, step by step, by the action of magnet R to again feed the carriage for printing and spacing.

In order to enable the carriage to be released manually or at will, I have shown the armature P' provided with a projection or finger piece P² shown projecting through an opening in plate 10^b (Figs. 9, 10 and 11), whereby said armature may be moved to cause it to be retained in the same position as when attracted by magnet P to release the pawl 85 and dog 97 from the ratchet wheel 86, thereby permitting the carriage to be returned to initial position. The pawl 85 and dog 97 are restored to normal by projection 89^a as heretofore described.

To resiliently check the carriage as it returns to normal, I provide a dash pot, shown in the form of a cylinder A and piston B, 85 shown secured adjacent to an edge of plate 10^b, said piston being in position to be engaged by a projection C secured upon rack 89 to drive the piston against air or spring resistance within chamber A. Upon the carriage (Figs. 9, 10 and 12), a spring pressed hook or dog D is pivotally supported at d (Fig. 12) and adapted to engage the head or enlargement b on piston B to draw the piston out of the cylinder A. The hook or dog D is provided with a pin or projection d' adapted to engage abutment D² depending from plate 10^b and shown as having a rounded outer edge and an inclined surface, (Fig. 12). The relation of these parts in such that, as the carriage returns toward normal, the hook or dog D will ride over the head b of piston B into position behind said head, and the projection C will engage the piston to resiliently resist its return. When the carriage steps forward a sufficient number of steps, such as corresponding to the length of dog D, during printing or spacing, the dog D will engage the piston head b and draw the piston outwardly, and when the pin d' engages the rounded corner of the abutment D² the dog D will be released from the piston.

The carriage may be of any suitable construction to carry the paper, and provided with means to feed the paper as required between member 14 and hammer 15. I have shown the carriage 90 provided with a paper carrying shaft 112 adapted to support a reel of paper 114. Said carriage is shown provided at one end with a bearing 115 for said shaft, (Fig. 11), and at the other end said carriage is shown provided with a slot at 116 (Fig. 9) through which the corresponding end of said shaft may pass. Upon the 125 corresponding arm of said carriage is slidably mounted a recessed locking piece 117, being shown provided with guiding slots 118 receiving screws 119 (Fig. 9), said slide piece having a toe 116^a adapted to overlie 130

shaft 112, being normally held in such position by a spring 120 (Fig. 11). The arrangement is such that when slide piece 116 is pushed back, as by its finger piece 116^a, shaft 112 may be removed and replaced. The paper 114 is led from the roll under a feeding roller 121 that is journaled in suitable bearings in carriage frame 90, and the paper is pressed against the feeding roller by a spring-pressed roller 122 journaled in arms 123 pivotally supported at 124 on carriage 90 (Figs. 9 and 11) and normally drawn upwardly by springs 125 (Fig. 9). From said rollers the paper is led upwardly between a rod 126 and a cutter plate 127 (shown provided with teeth) which parts are carried by the side uprights of carriage 90. Messages or the like that have been printed may be torn off from the web 20 of paper above cutter plate 127 by pulling the web along the cutter plate 127. Rod 126 is shown provided with spring fingers 128 depending along the back of the paper near its vertical edges, and adapted to retain the latter against rod 126 and to guide the edges of the paper, (Fig. 9). The arrangement of the carriage is such that paper 114 travels in the space between type member 14 and hammer 15, the carriage frame 90 being open 25 at its rear upper part between roller 121 and cutter 127 to permit the hammer to force the loosely supported upper portion of the paper toward member 14. In order to rotate the feeding roller 121 to feed the paper for line spacing, said roller is shown provided with a ratchet wheel 129 (Fig. 9) that is normally held from reverse rotation by a spring-pressed dog 130 pivoted upon the carriage, said roller being operated step by step by a 30 spring-acting pawl 131 pivotally carried by an arm 132 secured to a shaft 133 journaled upon carriage 90. Said arm is provided with a horizontally extending member 132^a (Figs. 9 and 11) secured at intervals to shaft 45 133 by suitable braces 134 (Fig. 10), whereby at any point at which said part 132^a is engaged, the arm 132 will be rocked to cause rotation of roller 121 for feeding the paper upwardly step by step for line spacing. To 50 this end I provide a finger or arm 135, shown located adjacent to bar 132^a and adapted to engage the same, said finger being at one side of the path of arm 18 and projecting through a slot in plate 10^a (Figs. 1 and 2). Finger 55 135 is to be operated by magnet M, and is shown secured upon a rock shaft 136 to which the armature of said magnet is secured (Figs. 7 and 8), which armature and finger are normally retracted by a spring 60 137. By this means, when said armature is energized the finger 135 will engage bar 132^a and rock the arm 132 to rotate paper feed roll 121 upon the return stroke of arm 132, in any position in which the paper carriage 65 may be located. Magnet M may be con-

trolled by a suitable key of the transmitting keyboard for causing line spacing of the paper when desired, as hereinafter explained.

Since the carriage is supported to travel upon the rollers 94, where it rests by gravity, I provide means to prevent the carriage from rising, which means may be retracted to permit insertion and removal of the carriage. To this end I provide a spring actuated pin 138 (Figs. 7, 8 and 9) guided in a bearing on bracket 11, said pin normally extending over rail 92 of the carriage (Fig. 9) to retain the latter upon corresponding rollers 94. When the carriage is to be inserted the spring drum is wound to a suitable extent and retained by dog 97, the hammer is swung to one side out of the path of the carriage, the pin 138 is withdrawn, the carriage is then inserted to rest upon the rollers 94, and pin 138 is released, to pass over rail 92.

Ribbon 140 (Figs. 6, 7, 8) is shown carried upon reels 141, 142, and above said reels, secured to bracket 11, is a vertical plate 143 having angularly disposed slots 143^a (Fig. 8), through which said ribbon is guided so that a portion of the ribbon passes transversely in front of plate 143 immediately between type member 14 and the web of paper projected upwardly in the carriage between roll 121 and cutter 127. Secured to plate 143 is a shield plate 144. To protect the paper from the ribbon I have shown an opening 144^a in plate 144 (Fig. 6) opposed to the hammer 15, for the latter to strike through to push the ribbon against the paper to produce the printing thereon from the type of member 14. The reels 141, 142 are loosely journaled upon a shaft 145, that is shown journaled in suitable brackets 105 depending from plate 10^a (Figs. 6, 7, 8 and 13). Collars 146 on shaft 145 limit movement of the adjacent reels outwardly, and at 147, 148 are springs bearing against said collars and against reels 141, 142 respectively, said springs being shown within recesses 141^a, 142^a within said reels, which springs push said reels respectively against stops or shoulders 149, 150 on shaft 145 (Fig. 13). The reels are suitably spaced 110 apart, and between said reels is a clutch member 151 shown having teeth 152 at its opposite ends, that engage teeth 153, 154 on said reels respectively. Clutch member 151 is keyed upon shaft 145 to rotate therewith and to slide thereon, and is of such width as to permit it to coact with only one reel at a time. To retain teeth of said clutch member in mesh with the teeth of one or the other of said reels, I have shown 125 said clutch member provided with interior notches 151^a (Fig. 13) engaged by a resilient stop 155, shown in the form of a spring-pressed ball set in a socket 156 in shaft 145, whereby member 151 may remain in set 130

position. To shift clutch member 151 from one reel to another, when the ribbon is about run off the latter reel, to cause rewinding of the ribbon thereon, I provide, for each 5 reel, a fork-like finger 157, one arm or prong of each finger being adapted to coact with the ribbon on the corresponding reel, (Figs. 6, 7 and 8), such fingers being pivotally supported upon a rod 158 carried 10 by plate 10^a. The other arm of each finger is alternately adapted to coact with member 151 to shift the latter longitudinally in one direction or another. The last named arms of said fingers are shown provided with 15 projections 157^a (Figs. 7 and 8) respectively adapted to coact with the cam faces 151^a, 151^b of member 151. Said fingers are normally drawn toward the reels and the clutch member by means of springs 159. The arrangement 20 is such that as shaft 145 is rotated, while the clutch member engages the teeth of a reel, it will wind the ribbon on such reel from the other reel which is then loose, and the finger 157 of the first named reel will gradually be moved away by reason of the increasing diameter of the ribbon being wound on such reel, and at the same time finger 157 of the other reel will approach shaft 145 by reason of the decreasing diameter 25 of the ribbon on such reel. When such ribbon is sufficiently unwound from the last named reel, the corresponding projection 157^a will be brought into such position as to engage the corresponding cam face of member 151, and thereupon, as such member continues to rotate the said cam face, by engagement with said projection, will cause 30 said member to slide along shaft 145, thereby releasing said member from the reel 35 having the greater amount of ribbon wound thereon and shifting said member into engagement with the reel having the less amount of ribbon thereon, whereupon the last named reel will now be rotated by shaft 40 45 145, and so on alternately. By reason of the springs 146 normally tending to push the reels toward member 151 the teeth of the clutch member 151 may resiliently engage the teeth 153 or 154 on the corresponding reel, and retain said teeth in engagement. Shaft 145 may be given a step by step rotation in any suitable manner. I have shown said shaft provided with a gear 160 in mesh with a pinion 161 secured on a 50 shaft 162 journaled in bearings carried by plate 10^a, to which shaft is secured a ratchet wheel 163 (Figs. 6, 7 and 8). A spring-acting pawl 164 is pivotally carried by an arm 165, shown secured to and depending 55 from shaft 79 controlled by the alinement magnet Q, whereby, as said magnet is operated, one of the ribbon reels will be rotated step by step. In the example illustrated I have utilized magnet Q for operating the 60 ribbon reels as a convenient magnet for the

purpose, since said magnet is energized each time a character is printed (Fig. 15), but it will be understood that the printing magnet T, or any other magnet, can be utilized to operate shaft 145 in the manner described, 70 by suitably connecting the armature of such magnet to arm 65 or otherwise to rotate said shaft.

In order to indicate audibly when the carriage about reaches the end of a printed line, I have shown a bell 166, carried upon a cover plate 167, that is shown pivotally supported at 168 upon plate 10^b (Fig. 9) inclosing said bell and the hammer when said cover is shut. Upon said cover I have 80 shown a post 179 to which a clapper 180 is pivotally connected, a spring 181 connected with said post and clapper serving to retain the latter toward the bell. Upon the paper carriage frame 90 is a projection 182 85 (Figs. 9 and 11), adapted to engage the pivoted and spring pressed dog 180^a of clapper 180, whereby when the carriage approaches the end of its line of travel the projection 182 will tilt and release the clapper to produce the signal on the bell, and when said projection returns it will tilt the dog 180^a in passing the same. 90

While the magnets hereinbefore referred to may be selected for operation and operated in any suitable manner, for the purpose of bringing the type member 14 into the desired position, and for operating the hammer and the other parts referred to, I have illustrated, in Fig. 15, a circuit selecting and controlling system that is particularly adapted to select and operate the said magnets as required. In Fig. 15 the normally open contacts 1^a, 2^a, 3^a, 4^a, 5^a and 5^b are, in the example under consideration, 105 adapted to be closed and opened successively, (in one, two, three order) except that the contacts 5^a and 5^b are preferably operated together. Means to operate said contacts may comprise a suitable translator 110 having a shaft W provided with cams for operating said contacts, in conjunction with means controlled by signals or impulses on line 50, (sent over the line by any suitable means) to actuate relay 51 to send a signal 115 on branch 55, to start or cause operation of such cams. A particular means whereby said relay and contacts may be operated is disclosed in application Serial No. 860,318. The relays 1^b, 2^b, 3^b, 4^b, 5^b and E are adapted to be controlled by current flowing 120 through the contacts 1^a, 2^a, 3^a, 4^a, 5^a and 5^b respectively, provided that current is on line 50 to cause relay 51 to attract its armature 51^a, for closing circuit at contact 54, 125 at such time that any one of said contacts 1^a, 2^a, 3^a, 4^a, 5^a is closed. Said relays 1^b, 2^b, 3^b, 4^b, 5^b, E correspond to the relays 1^b, 2^b, 3^b, 4^b, 5^b, 6^b in my aforesaid application Serial No. 860,318, and also correspond to 130

the relays 1, 2, 3, 4, 5 and E in my aforesaid application Serial No. 801,813. It will, however, be understood that said relays may be controlled in accordance with the disclosure in either of my said applications. The said relays 1^b, 2^b, 3^b, 4^b, 5^b control the magnets 1^d, 2^d, 2^{d''}, 3^d, 3^{d''}, 4^d, 5^d, which magnets (except 2^{d''}, 3^{d''}) correspond to the magnets correspondingly marked in my said application 801,813. Resistances 59^a and 70 are for the purpose of preventing excessive flow of current through any of relays, 1^b, 2^b, 3^b, 4^b, 5^b. The relays I and J herein, shown respectively in circuit with the relays 4^b, 5^b, correspond to the relays I and J respectively in circuit with the relays 4 and 5 of my said application Serial No. 801,813. The other relays shown in Fig. 15 hereof correspond to relays correspondingly lettered in my last named application. It thus will be understood that, while I have herein illustrated relays and magnets for controlling the operation of my improved telegraph typewriting machine in some measure corresponding to the control of the corresponding relays in my application Serial No. 801,813, I have modified and simplified the means for controlling said relays shown in said application, and in so doing have utilized features corresponding to my application 860,318, for the purpose of selecting and energizing said relays as required.

Current may be sent over line 50 in any suitable manner, as, for instance, from a transmitting translator having contacts operating isochronally with the contacts 1^a, 2^a, 3^a, 4^a, 5^a, to transmit current through said contacts when closed, in accordance with the magnets 1^d, 2^d, 3^d, 4^d, 5^d required to be operated, to print any desired character, as well as through relay E for producing certain operations of said typewriter, and that current, as required, may be transmitted over line 50 by means, such as a key-controlled transmitter, disclosed in my said applications Serial Nos. 742,211 and 860,318.

Whenever the line relay 51 is operated for a group or series of signals it will cause closing of contacts 1^a, 2^a, 3^a, 4^a, 5^a successively, and 5^x simultaneously with 5^a. Whenever relay 51 is operated, at the time that a contact 1^a, 2^a, 3^a, 4^a, or 5^a is closed, the corresponding relay 1^b, 2^b, 3^b, 4^b, 5^b will be energized, so that if at the time that any of said contacts is closed the relay 51 is not energized, the corresponding relay 1^b, 2^b, 3^b, 4^b, 5^b will not be energized. The operation of relays 1^b, 2^b, 3^b, 4^b, 5^b will cause operation of their armatures 1^c, 2^c, 3^c, 4^c, 5^c whereby the maintenance of a holding circuit through the operated relays 1^b, 2^b, 3^b, 4^b, 5^b and their corresponding magnets 1^d, 2^d, 2^{d''}, 3^d, 3^{d''}, 4^d and 5^d will be effected.

When relay 4^b is energized the operation of relay I will be caused, whose two armatures I' and I² will operate together. Whenever relay 5^b is operated the operation of relay J will be caused to operate its armature J'. Relay H operates with any (one or more) of the relays 1^b, 2^b, 3^b, 4^b, 5^b, and relay G operates only when relays 1^b, 2^b, 3^b, are operated in succession on a given signal on the line.

Assuming that a group or series of six signals or impulses are sent over line 50, to cause any desired operation or operations of the telegraph typewriter hereinbefore described, it will be understood that the first of such signals or impulses will start or cause the operation of means to close contacts 1^a, 2^a, 3^a, 4^a, 5^a successively (and 5^x with 5^a) in the example illustrated, as by starting the operation of said cam shaft W. The five succeeding signals may comprise current on line 50 or not. If, while one or more of the contacts 1^a, 2^a, 3^a, 4^a or 5^a is closed, current flows on line 50, then relay 51 will be operated to cause circuit to be closed at 51^a and 54, from ground through battery or generator 58', conductor 67, contact 54, through resistances 59^a and 70, thereby causing the operation of any of the magnets 1^d, 2^d, 2^{d''}, 3^d, 3^{d''}, 4^d, 5^d, through such corresponding closed contact or contacts (also causing the operation of any relay that may be in circuit with such operated magnet). For each of such contacts through which current does not then flow, none of such magnets or their corresponding relays will be operated. By this means the selection and operation of the desired magnet, or magnet and relay therewith (or one or more relays independent of such magnet) for a required operation of the apparatus, may be effected.

Contact 5^x and relay E.—When contact 5^x is closed relay E will be energized from battery 58', conductor 67, contact 5^x, through relay E to ground. Relay E will attract its armature E', connecting one side of winding of relay F to E, the other side of relay F being normally connected through armature L' to the positive side of battery 58'. During the time that contact 5^x is closed and relay F is connected to relay E through armature E', the winding of F will be short-circuited, for the reason that one side is connected to 5^x through armature E' and the other side of relay F is also connected to 5^x through armature L' and conductor 67. As soon as circuit is broken at 5^x the relay F will be operated (by reason of such break) and relays E and F will remain energized, from the positive side of battery 58', armature L', relay F, armature E', relay E to ground, until circuit of E and F is broken at L'.

Relay H.—Whenever any of relays 1^b, 2^b, 3^b, 4^b, 5^b are operated circuit will be estab-

lished through relay H, operating its armature H'. Each time that relay H is energized its armature switches from the circuit of figure-release magnet S to the circuit of printing magnet T, so thereafter (during a group of signals) any current flowing through armature H' will pass through magnets T, R and Q, instead of through magnets S, R and Q (as when H' is in its normal position). The normal operating circuit for relay H may be traced from the positive side of battery 58' to armature I', relay H, through armature 4^a or 5^a or 4^b and 5^b (if either or both are operated), through the corresponding relay 4^b or 5^b or both, relay I or J, or both, and through magnets 4^a or (and) 5^a to ground and negative side of 58'. If any one or two of relays 1^b, 2^b, 3^b is energized circuit will be established from battery, as above described, through H, through the normally closed contact and armature of the relay or relays of the group 1^b, 2^b, 3^b not operated, thence through the corresponding armature of such relay or relays as have been operated, thence through the corresponding magnet 1^a, 2^a, 3^a to the negative side of battery 58'. If the three relays 1^b, 2^b, 3^b have been operated for a given group of signals, the armatures 1^c, 2^c, 3^c will be removed from their back contacts and circuit through H will be established from the positive side of battery through armature I', H and relay G, thence through the armatures 1^c, 2^c, 3^c, through relays 1^b, 2^b, 3^b, through their corresponding magnets 1^a, 2^a, 2^a', 3^a, 3^a' to the negative side of battery. It thus will be noted that if any of the relays 1^b, 2^b, 3^b, 4^b, 5^b are operated, the relay H also will be operated.

40. *Relay G.*—Relay G is short circuited normally by armatures 1^c, 2^c, 3^c of relays 1^b, 2^b, 3^b, and it requires the combined action of 1^b, 2^b, 3^b to permit relay G to be energized, so that G will be energized only whenever relays 1^b, 2^b, 3^b are operated together, circuit then being established from positive side of battery 58', armature I', relay H, relay G, through armatures 1^c, 2^c and 3^c, through relays 1^b, 2^b, 3^b, through their respective magnets 1^a, 2^a, 2^a', 3^a, 3^a' to ground and negative side of the battery. When relay G is operated it will break circuit from armature H' and establish circuit to armature J'.

45. *Relay J.*—When relay J is operated its armature J' breaks circuit with armature I² and closes circuit to armature I'. Armature J' always operates with relay 5^b.

50. *Relay I.*—Relay I operates its armatures I' and I² to simultaneously break the connection with line-space magnet M and the carriage return magnet P, and establish connection to back-space magnet N and figure-shift magnet O. Armatures I', I² always operate with relay 4^b.

55. *Relay F.*—When relay F is energized, 65 it will attract its armature F', and current will flow from the positive side of battery 58', through F', relay L, through the armature G' of relay G, thence to armature H' of relay H, (if relay G has not been operated), thence through magnets S, Q and R to ground if relay H has not been operated, and through armature H', and relays T, R and Q if H has been operated. If relay G had been operated, the circuit would 70 have been completed from F', when operated through relay L, armature G', to armature J' of relay J, and thence (if relay J had not been operated) to armature I² of relay I, thence through line-space magnet 80 M to ground. If relay I had been energized then the circuit would have been through I² and back-space magnet N to ground. If relay J had been operated its armature J' would have closed circuit to armature I' and thence through carriage return magnet P to ground, if relay I had not been operated. If relays J and I had both been operated circuit would be established through figure shift magnet O. 90

95. *Relay L.*—Relay L is for the purpose of restoring all operated relays and magnets to normal. It accomplishes this result by opening, at L', the holding circuit for all other relays retained energized by reason of their respective holding circuits, when circuit is established through relay L upon the operation of F' by relay F, but the operation of relay L is so timed that the proper functioning of the apparatus will have taken place before the respective controlling circuits have been broken by the operation of relay L. 100

105. The timing of relay L may be controlled by varying its air gap and its spring tension as well as by shunting it with a non-inductive resistance L*, and the duration of opening contact at armature L' may be governed by the non-inductive resistance L* or other suitable magnet control. 110

115. The operation of the telegraph typewriter hereinbefore described, in conjunction with the relays and circuit system illustrated in Fig. 15, may be described as follows:

120. At a transmitting station of the system a suitable transmitter may be located having keys adapted to control the operation of line relay 51 and so organized, in the example illustrated in Fig. 15, that when the first of a series of signals is set on line 50, relay 51 will be energized to cause the cam shaft W to operate, and whereby, for each one of the contacts 1^a, 2^a, 3^a, 4^a, 5^a through which current is intended to be sent, the relay 51 will be further caused to operate to attract its armature 51^a, so that contact will be closed at 54 at the start and during the time that the required contact 1^a, 2^a, 3^a, 4^a, 125

or 5^a is closed, whereby to cause operation of the corresponding relay 1^a , 2^b , 3^b , 4^b , or 5^b as required for the operation of selecting the type character to be printed, printing, and performing other operations of the machine before described. Current may be sent over line 50 according to the system set forth in my aforesaid application Serial No. 860,318, for causing operation of cam shaft 16 21 and the sending of desired signals over line 50, or the magnets of the printing telegraph herein-described may be caused to operate by the means set forth in my aforesaid application Serial No. 801,813 for controlling system for receiving apparatus. Assuming that my present improvements are to be used in conjunction with the transmitting mechanism disclosed in my aforesaid application Serial No. 860,318, and that it is 20 desired to space the carriage forward without printing any character, a signal may be transmitted on line 50, such as to start the operation of cam shaft W, which will cause closing of contacts at 1^a , 2^a , 3^a , 4^a , 5^a and 5^b , but current is only sent through said contact 5^a . Such current sent through contact 5^a causes operation of magnet E, closing circuit at E', and thence to the word space magnet R, and the latter, with alining magnet Q and figure-release magnet S, will be operated because of current flowing from positive side of battery 58', in the manner described under the heading "Contact 5^a and relay E." It will thus be noted that under such conditions of the circuit, magnet R will be energized to advance the carriage the space of one letter, and the type member 14 will be released and restored to normal if it has been previously shifted to 30 the "figure-shift" position by the operation of magnet S, the magnet Q always operating the type member alining devices under such conditions (as a matter of convenient construction), and also operating the inking ribbon feed.

If it is desired to print a character and advance the carriage a character space, it will be necessary to energize the magnets T, R and Q (operating Q to lock member 14 during the printing operation). To this end it is necessary that relay H be energized to throw magnet T into circuit and cut out the magnet S. Relay H will be operated by the operation of any of the relays 1^b , 2^b , 3^b , 4^b , 5^b as described under paragraph entitled "Relay H." The particular character will be determined by the magnets 1^a , 2^a , 2^b , 3^a , 3^b , 4^a or 5^a operated, or combinations of such magnets, as hereinbefore described, in accordance with the signal that may be sent over line 50 through any of the contacts 1^a , 2^a , 3^a , 4^a , or 5^a , singly or in the desired succession or combination. The foregoing pertains to the printing and spacing operations of the apparatus while the member 14 is in the normal or first position, and also applies provided said member 14 has previously been shifted to the "figure-shift" or second position.

When it is desired to advance the paper 70 to a new line or for line spacing, a key of the keyboard is depressed, such as to cause operation of relays 1^b , 2^b , 3^b , which will cause operation of relay G, so that when armature F' is closed by operation of contact 5^a and armature E', as heretofore described, circuit will be established through relay L, armature G', closed contact of unoperated armature J', through armature I', and through line space magnet M, to negative 80 side of battery.

When it is required to back-space the carriage, a signal will be transmitted on the line, such as to operate the relays 1^b , 2^b , 3^b and 4^b and close contact 5^a . Operation of 4^b 85 will cause operation of relay I, and operation of 1^b , 2^b , 3^b will cause operation of relay G, so that when relay F is operated the circuit will be established from battery 58', armature F', relay L, operated armature G', unoperated armature J', operated armature I', through back space magnet N, to negative side of the battery.

When carriage return is required, a suitable key of the keyboard is operated to cause 95 operation of relays 1^b , 2^b , 3^b and 5^b and to close circuit at 5^a . Operation of 1^b , 2^b and 3^b will cause operation of relay G. Operation of relay 5^b will cause operation of relay J, and armature J' will make connection with the non-operated armature I', establishing a circuit for the carriage return magnet P, from the positive side of the battery, through armature F', release relay L, operated armature G', operated armature J', non-operated armature I', through carriage return magnet P and back to negative side of battery.

To cause the type member 14 to be moved to the second or "figure shift" position, a key of the keyboard corresponding to "Fig. shift" is operated, causing the operation of relay 51 to energize all of relays 1^b , 2^b , 3^b , 4^b , 5^b in succession by suitable signals on the line, and to close contact 5^a . The operation of relays 1^b , 2^b and 3^b causes relay G to be 110 energized. The operation of relays 4^b and 5^b causes relays I and J to be operated to shift their armatures, and a circuit will be established for "figure-shift" magnet O when 5^a is closed, from the positive side of battery 58' to operated armature F', release relay L, operated armature G', operated armature J', operated armature I', and through "figure-shift" magnet O to negative side of battery. The operation of magnet O causes arm 18 to be moved to the "figure-shift" position to be retained by stop 49.

While the arm 18 is in the "figure-shift"

position signals may be sent over line 50 for printing characters in the second portion of member 14 without requiring arm 18 to be returned to first normal. To return arm 18 to first normal, the spacing key of the keyboard will be operated to operate magnet S, as described under "Word spacing".

The operations regarding the rotation of member 14 occur in a similar manner in any of its positions of elevation, or with respect to either of its rows of type. Since said member normally rests, in the example illustrated, with its row of type 14^a in register with hammer 15, it will be necessary to cause operation of magnet 4^a or 5^a, or said magnets together, in order to raise member 14 one, two or three spaces from normal to bring a corresponding row of type opposite the hammer, as before explained. If it be desired to print a character so positioned on the member 14 as would necessitate a rotation as well as a vertical shift, rotation will be caused by operation of magnets 1^a, 2^a and 3^a separately or in combination, with the magnets 4^a or 5^a, or 4^a and 5^a to elevate the wheel to the particular row upon which the character is positioned. In other words, it will be understood that the magnets 1^a, 2^a and 3^a will be utilized to rotate type member 14 whether or not the magnets 4^a, 5^a are used to cause longitudinal movement of said type wheel. It will be seen that it is possible to position any one of twenty-eight characters opposite the type hammer 15 by suitable combinations of magnets 1^a, 2^a, 3^a, 4^a and 5^a, except that when relays 1^b, 2^b, and 3^b are operated together the relay G will be operated to cut out the printing and spacing functions and substitute the working functions, namely, line space, back-space, "figure-shift", and carriage return. The particular working function will be determined by the operation or non-operation of relays 4^b or 5^b or 4^b and 5^b, as before described.

It will be understood that after a series or succession of signals have been sent over line 50, to cause the printing operation or any of the other working functions of the machine, and the closing of contact 5^x and operation of relay E, the timing of printing magnet T, spacing magnet R and alining magnet Q, preparatory to their operating, is governed by the adjustment of relays E and F, so that if it is desired to have a long interval of time after the operations of relays 1^b, 2^b, 3^b, 4^b, 5^b and their corresponding magnets 1^a, 2^a, 3^a, 4^a, 5^a, the relays E and F may be so adjusted as to be relatively slow in action. After relay F has been operated and a circuit is established through relay L and the particular working magnets previously selected, they will be maintained energized until relay L has operated to open the

normally closed contact in the holding circuit at L'. The time that the holding circuit is open to permit magnets and relays to return to normal (with the exception of relay L itself) is determined by the time that relay L remains operated. In order to insure proper timing for correct operation, and also to insure high speed, it is desirable that the time between the selection of a function and the operation of that function should be as rapid as practical, but be capable of an adjustment. It is also desirable to vary the duration of magnetization of the working function magnets, and to insure correct operation it is necessary that the holding circuits of the relays 1^b, 2^b, 3^b, 4^b, 5^b and E shall be open for a sufficient length of time to permit them to be restored to normal. The time previous to actual operation of the working functions is governed by the adjustment of relays E and F. The time of operation is governed by the time that is required for relay L to operate, and armature I' to be restored to normal, which may be varied by changing the air gap and spring tension of armature L'. The time during which the holding circuit for relays 1^b, 2^b, 3^b, 4^b, 5^b and E is open is governed by the time that relay L' remains in its operated position, which may be governed by the non-inductive resistance L^a in shunt with relay L.

While I have shown relay I permanently in circuit with relay 4^b to operate the armatures I¹, I², and relay J permanently in circuit with relay 5^b to operate armature J, it will be understood that the relays I and J may be dispensed with and that the contacts controlled by the armatures I¹, I² may be controlled by the relay 4^b and that the contacts controlled by armature J may be controlled by relay 5^b.

It will be understood that the relays 1^b, 2^b, 3^b, 4^b, 5^b, I and J may be considered to be a group of relays divided into two sections, a first section of which may be considered to comprise the relays 1^b, 2^b, 3^b and the second section of which may be considered to comprise the relays 4^b, 5^b, I and J, and since relays I and J always work with the corresponding relays 4^b, 5^b, the relays 4^b and I and the relays 5^b and J may be considered as one relay of the second section of the group; the relays G and H may be considered to be a second group of relays, and the relays E, F and L may be considered to be a third group of relays, it also being understood that one of the relays (H) of the second group is controlled by relays of either section of the first named group, and that another relay of the second group (G) is controlled only by the relays of one section of the first named group, and that the relays of the third group are controlled independently of the relays of either of the first and second groups.

Having now described my invention what I claim is:—

1. In a telegraph typewriter, the combination of a type member, an arm pivotally supported relatively to said type member, means coactive between said type member and arm to rotate the former by the latter, means to retain said arm in a normal position, means to shift said arm and type member to a second position, means to retain said arm in said second normal position, means to operate said retaining means to release said arm, and means to move said arm progressively between said normal positions and beyond the second normal position, said means permitting said arm to be returned to, and be retained in said second normal position.

2. In a telegraph typewriter, the combination of a type member, an arm pivotally supported relatively to said type member, means coactive between said type member and arm to rotate the former by the latter, means to retain said arm in a normal position, a magnet having an armature, means connecting said armature with said arm for shifting said arm to a second normal position, a stop to retain said arm in said position, a magnet to operate said stop to release said arm, and means to cause said arm to move said type member from either of said normal positions.

3. In a telegraph typewriter, the combination of a type member, an arm pivotally supported relatively to said type member, means coactive between said type member and arm to rotate the former by the latter, means to retain said arm in a normal position, means to shift said arm and type member to a second position, means to retain said arm in said normal position, means to operate said retaining means to release said arm, a second arm, means for pivotally supporting said arms for movement together and relatively one to another, means operatively located with respect to said arms for moving said arms together and for moving the first named arm relatively to the second named arm, and means for actuating the last named means to move the first named arm one or more spaces.

4. In a telegraph typewriter, the combination of a type member, an arm pivotally supported relatively to said type member, means to retain said arm in a normal position, means to shift said arm to a second normal position, means to retain said arm in said second normal position, means to operate said retaining means to release said arm, a second arm, means pivotally connecting said arms for movement together and relatively one to another, and for permitting said second named arm to move relatively to the first named arm, and means connecting said last named means with said type mem-

ber for moving the latter by and with said arms.

5. In a telegraph typewriter the combination of a pair of arms, means pivotally supporting said arms for separate articulation, means pivotally connecting said arms whereby longitudinal movement of one arm imparts lateral movement to the other arm, and vice versa, and means to separately operate said arms, a movable member, means connecting said member with the second named means for operation of said member by either of said arms or by the conjoint movement of said arms.

6. In a telegraph typewriter the combination of a pair of arms, means pivotally supporting said arms for separate articulation, means pivotally connecting said arms whereby longitudinal movement of one arm imparts lateral movement to the other arm and vice versa, means to separately operate said arms, means to retain one of said arms in an operated position, means to release said retaining means, a movable member, means connecting said member with the second named means for operation of said member by either of said arms or by the conjoint movement of said arms.

7. In a telegraph typewriter the combination of a pair of arms, means pivotally supporting said arms for separate articulation, means pivotally connecting said arms whereby longitudinal movement of one arm imparts lateral movement to the other arm, and vice versa, means to separately operate said arms, a movable member, means connecting said member with the second named means for operation of said member by either of said arms or by the conjoint movement of said arms, and means for operating the second named means separately from its operation by either of said arms for moving said member separately from its movement by either of said arms.

8. In a telegraph typewriter, the combination of a type member, an arm pivotally supported relatively to said type member, means coactive between said type member and arm to rotate the former by the latter, means to retain said arm in a normal position, means to shift said arm and type member to a second normal position, means to retain said arm in said second normal position, means to operate said retaining means to release said arm, a second arm, means for pivotally supporting said arms for movement together and relatively one to another, means operatively located with respect to said arms for moving said arms together and for moving the first named arm relatively to the second named arm, a magnet having an armature connected with said arm-operating means for moving the first named arm from either of its normal posi-

tions, a third magnet, and means connecting the armature of the third named magnet with said arm operating means independently of or in conjunction with its movement by the first named magnet.

9. In a telegraph typewriter, the combination of a type member, an arm pivotally supported relatively to said type member, means coactive between said type member and arm to rotate the former by the latter, means to retain said arm in a normal position, means to operate said retaining means to release said arm for another normal position, a second arm, means for pivotally supporting said arms for movement together and relatively one to another, means operatively located with respect to said arms for moving said arms together and for moving the first named arm relatively to the second named arm, a magnet having an armature connected with said arm operating means for moving the first named arm from either of its normal positions, a second magnet, and means connecting the armature of the second named magnet with said arm operating means independently of or in conjunction with its movement by the first named magnet, a stop normally in the path of the means operated by the second named magnet, and a magnet to actuate said stop to withdraw it from said means.

10. In a telegraph typewriter, the combination of a type member, an arm pivotally supported relatively to said type member, means coactive between said type member and arm to rotate the former by the latter, means to retain said arm in a normal position, means to shift said arm and type member to a second position, means to retain said arm in said second normal position, means to operate said retaining means to release said arm, a second arm, means for pivotally supporting said arms for movement together and relatively one to another, means operatively located with respect to said arms for moving said arms together and for moving the first named arm relatively to the second named arm, a magnet having an armature connected with said arm operating means for moving the first named arm from either of its normal positions, a second magnet, and means connecting the armature of the second named magnet with said arm operating means independently of or in conjunction with its movement by the first named magnet, spaced stops normally in the path of the means operated by the third named magnets, and magnets to separately operate said stops.

60 11. In a telegraph typewriter, the combination of a type member, an arm, means coactive between said type member and arm to operate the former by the latter, a second arm, means pivotally supporting

said arms to move together and to permit the first named arm to move separately from the second named arm, a slide, means operatively connecting said slide with the second arm, a magnet to operate said slide, a cam, means to cause said cam to actuate the first named arm, a second magnet, means operatively connecting said magnet with said cam, a third magnet, means operatively connecting said third magnet with said arms, means to retain said arms in a normal position, means to retain said arms in a second normal position when operated by said third magnet, and means to actuate said retaining means to release said arms from said second normal position.

12. In a telegraph typewriter, the combination of a type member, an arm, means coactive between said type member and arm to operate the former by the latter, a second arm, means pivotally supporting said arms to move together and to permit the first named arm to move separately from the second named arm, a slide, means operatively connecting said slide with the second arm, a magnet to operate said slide, a cam, means to cause said cam to actuate the first named arm, a second magnet, means operatively connecting said magnet with said cam, a third magnet, means operatively connecting said third magnet with said arms, means to retain said arms in a normal position, a stop to retain said arms in a second normal position, and a magnet to actuate said stop to release said arms from said second normal position.

13. In a telegraph typewriter, the combination of a type member, an arm, means coactive between said type member and arm to operate the former by the latter, a second arm, means pivotally supporting said arms to move together and to permit the first named arm to move separately from the second named arm, a slide, means operatively connecting said slide with said second arm, a magnet to operate said slide, a cam, means to cause said cam to actuate the first named arm, a second magnet, means operatively connecting said second magnet with said cam, an arm connected with said cam, a third magnet having an armature connected with said arm, means to retain said armature and said arms in a normal position, a stop to retain said armature and arms in a second normal position, and a magnet to actuate said stop to release said armature and arms from said second normal position.

14. In a telegraph typewriter the combination of a type member, a pivotal arm, means operatively connecting said member with said arm, a magnet, means operatively connecting said magnet and arm for moving the latter by the former, a second magnet,

- means operative between the second magnet and said arm for moving the latter separately from its movement by the first named magnet, a third magnet, and means operative by said third magnet for actuating said arm independent of its actuation by either of the first named magnets without varying the extent of movement of the devices controlled by the first named magnets.
- 10 15. In a telegraph typewriter the combination of a type member, a pivotal arm to operate said member, a cam to actuate said arm, a magnet having its armature operatively connected with said cam, a second arm, means operatively connecting said cam with said second arm, a second cam to operate said arm, a magnet, means operatively connecting said magnet with the second cam whereby said arms may be moved together, 20 and means to move said arms bodily from one position to another.
16. In a telegraph typewriter the combination of a type member, a pivotal arm to operate said member, a cam to actuate said arm, a magnet having its armature operatively connected with said cam, a second arm, means operatively connecting said cam with said second arm, a second cam to operate said arm, a magnet, means operatively connecting said magnet with the second cam whereby said arms may be moved together, 25 a third magnet, and means operatively connecting said magnet with said second arm for moving said arms and cams together 30 from one position to another.
17. In a telegraph typewriter the combination of a type member, a pivotal arm to operate said member, a cam to actuate said arm, a magnet having its armature operatively connected with said cam, a second arm, means operatively connecting said cam with said second arm, a second cam to operate said arm, a magnet, means operatively connecting said magnet with the second cam whereby said arms may be moved together, 35 a third magnet, an arm operatively connecting the second cam with the armature of said magnet for moving said arms and cams together.
- 40 18. In a telegraph typewriter the combination of a type member, a pivotal arm, means operatively connecting said member with said arm, a magnet, means operative between said magnet and arm for moving the latter by the former, a second magnet, a cam, means operatively connecting said cam with the armature of said magnet, means to operate said arm by said cam, a third magnet, and means operatively connecting the cam with the armature of the third magnet.
- 45 19. In a telegraph typewriter the combination of a type member, a pivotal arm, means operatively connecting said member with said arm, a magnet, means operative 50 between said magnet and arm for moving the latter by the former, a second magnet, a cam, means operatively connecting said cam with the armature of said magnet, means to operate said arm by said cam, a third magnet, means operatively connecting the cam with the armature of the third magnet, a stop to retain the cam in position when operated by the third magnet, and means to release said stop.
- 55 20. In a telegraph typewriter the combination of a type member, a pivotal arm to operate said member, a cam to actuate said arm, a magnet having its armature operatively connected with said cam, a second arm, means operatively connecting said cam with said second arm, a second cam to operate said arm, a magnet, an arm pivotally connecting the second cam with the armature of the second named magnet, a third magnet, and means pivotally connecting the second named cam with the armature of the third named magnet.
- 60 21. In a telegraph typewriter, the combination of a type-bearing surface, an arm adapted to move said surface, a pivoted cam adapted to move said arm, means for shifting the pivotal point of said cam, and means for locking the shifting means in shifted position.
- 65 22. In a telegraph typewriter, the combination of a type-bearing surface, an arm adapted to move said surface, a pivoted cam adapted to move said arm, means for shifting the pivotal point of said cam, means for locking the shifting means in shifted position, magnets for actuating said cam and said shifting means and for releasing said locking means and springs for returning said cam and shifting means to normal 70 position.
- 70 23. In a telegraph typewriter, the combination of a type-bearing surface, an arm adapted to move said surface, a cam adapted to move said arm, a second cam also adapted to move said arm, and means for changing the operating positions of both of said cams.
- 75 24. In a telegraph typewriter, the combination of a type-bearing surface, an arm adapted to move said surface, a cam adapted to move said arm, a second cam also adapted to move said arm, means for changing the operating positions of both of said cams, magnets for actuating said cams, and springs for returning said cams and means 80 to normal position.
- 80 25. In a telegraph typewriter, the combination of a type-bearing surface, an arm adapted to move said type-bearing surface, a cam adapted to shift said arm, a second cam also adapted to shift said arm relatively to said first-mentioned cam, and common means for changing the operating positions of both of said cams without changing their operating relation.

26. In a telegraph typewriter, the combination of a type-bearing surface, an arm adapted to move said type-bearing surface, a cam adapted to shift said arm, a second cam also adapted to shift said arm and at the same time change the operating position of said first-mentioned cam, common means for shifting the positions of both of said cams, and means for locking said common means in shifted position. 5 70
27. In a telegraph typewriter, the combination of a type-bearing surface, a shiftable member operatively connected therewith, means for shifting said member to effect a predetermined vertical movement of said surface, a cam pivoted on said member, and means for moving said cam about its pivot to effect a predetermined vertical movement of said surface. 15 75
28. In a telegraph typewriter the combination of a reciprocating printing hammer, a pivoted guide therefor adapted to be shifted to place said hammer in effective or ineffective position, means for retaining said guide in a shifted position, means for positively advancing said hammer, and spring actuated means for retracting said hammer. 20 80
29. In a telegraph typewriter, the combination of a reciprocating printing hammer, a pivoted guide therefor adapted to be shifted to place said hammer in effective or ineffective position, means for retaining said guide in a shifted position, means for positively advancing said hammer, spring actuated means for retracting said hammer, and yieldable means mounted on said advancing means for constraining the retractile movement of said hammer when said guide is shifted. 30 85
30. In a telegraph typewriter, the combination of a carriage, a spring, means for advancing the carriage step by step against the tension of said spring, means adapted to permit said spring to retract said carriage step by step, and means to permit said spring to completely retract said carriage with a single continuous movement. 40 90
31. In a telegraph typewriter, the combination of a carriage, a spring normally tending to retract said carriage, means for advancing the carriage step by step against the tension of the spring, means adapted to permit said spring to retract said carriage step by step by means of the spring, means to permit said spring to completely retract said carriage with a single continuous movement, and magnets for actuating each of said means. 50 95
32. In a telegraph typewriter, the combination of a carriage, a spring normally tending to retract said carriage, a ratchet connected to said spring, pawls normally in engagement with said ratchet to prevent the retraction of said carriage, a pawl normally out of engagement with said ratchet, means 60 100
- adapted to disengage said first-mentioned pawls from the ratchet and to engage the last-mentioned pawl therewith, to permit the retraction of the carriage step by step by the spring, means adapted to permit the complete continuous retraction of said carriage comprising means for dis-engaging said first-mentioned pawls from the ratchet but permitting said last-mentioned pawl to remain in normal position, and means to actuate one of said first-mentioned pawls to advance the carriage against the tension of the spring. 65 105
33. The combination of a frame, a carriage, means to move said carriage in opposite directions with respect to said frame, a dash pot comprising a cylinder and plunger adapted to resiliently resist movement of the carriage as it approaches its limit of movement in one direction, means to withdraw the plunger after a predetermined advance of the carriage in the opposite direction, means to release the plunger from said withdrawing means after the plunger has been drawn with respect to the cylinder of the dash pot. 75 110
34. The combination of a magnet having an armature, means to retain the armature in a normal position, spaced stops spaced from said armature and normally in the path of the armature, means to separately operate said stops and to operate said stops together to remove the stop or stops from the path of the armature. 80 115
35. The combination of a magnet having an armature, means to retain the armature in a normal position, spaced stops spaced from said armature and normally in the path of the armature, a magnet for operating each of said stops, and means for causing operation of one or the other of said second named magnets upon energization of said first named magnet to remove the stop or stops from the path of the armature. 85 120
36. The combination of a magnet having an armature, means to retain the armature in a normal position, spaced stops spaced from said armature and normally in the path of the armature, a magnet for operating each of said stops to remove the stop or stops from the path of the armature, means for causing operation of one or the other of said second named magnets upon energization of said first named magnet, and means for causing operation of the second named magnets together upon energization of the first named magnet. 90 125
37. A circuit controlling system comprising a group of relays, said group having a plurality of sections comprising each a plurality of relays, a second group of relays, one of the relays of the second group being controlled by relays individually of the first group and another relay of the second group being controlled by the collective action of 95 130

the first section of relays of the first named group, the relays of the third named group causing circuits to be utilized as organized by the operation of relays of the first named group, relays of the third group together controlling the time before actual completion of the circuits through the magnets controlled by the relays of the first group, another relay of the third group controlling 10 the time during which the circuit is completed through the magnets controlled by the relays of the first group, said relay of the third group being provided with a resistance in shunt with the circuit thereof for 15 the purpose of prolonging the time of magnetization after the circuit through said relay has been broken.

38. In a telegraph typewriter, the combination of a type member, means to rotate 20 said member, resiliently acting means to aline the type member in printing position, and a magnet to actuate said means.

39. In a telegraph typewriter, the combination of a type member, means to rotate 25 said member, means to move said member longitudinally, means to aline the type member in its rotated and longitudinal positions, a magnet to operate said alining means together, and resilient means operative between said magnet and said alining means for transmitting movement to the latter.

40. In a telegraph typewriter, the combi-

nation of a type member, means to rotate said member, means to move said member 35 longitudinally, a shaft having a saddle, arms loosely mounted upon the shaft, springs interposed between said saddle and arms, means coactive with one of said arms and the means that rotate said member for alining the latter in rotated position, means coactive between the other arm and the means that move the member longitudinally for alining said member in a position of longitudinal adjustment, and means to rock said 40 shaft.

41. In a telegraph typewriter, the combination of a type member, means to rotate said member, an arm having means to aline said type member in rotated positions, a 50 shaft carrying said arm, ribbon spools, means to guide a ribbon from said spools in printing position with respect to said type member, a second arm operative by said shaft, means operated by said arm for rotating said ribbon spools, means for shifting said last named means for operating said spools successively, and a magnet to operate said shaft.

Signed at New York city, in the county 60 of New York, and State of New York, this 9th day of April, A. D. 1915.

ALLEN D. CARDWELL.

Witness:

T. F. BOURNE.
